UNITED STATES PATENT OFFICE.

ROGER J. SWEET, OF BUFFALO, NEW YORK.

VAPOR-CONTROLLING SYSTEM FOR ENGINES.

Application filed January 7, 1920. Serial No. 349,342.

To all whom it may concern:

Be it known that I, ROGER J. SWEET, a citizen of the United States, residing at Buffalo, in the county of Erie and State of New York, have invented new and useful Improvements in Vapor-Controlling Systems for Engines, of which the following is a specification.

This invention relates to an internal combustion vapor motor or gas engine which derives its power from the igniting of a compressed charge of air and fuel.

One of the objects of the invention is to provide for the feeding of a heated and definitely measured quantity of compressed gas into the engine cylinder.

A further object of the invention is to provide for this measuring and heating of the compressed gas in a special or supplemental gas measuring chamber, which functions as an independent part of the engine, so that the presence of gasoline vapor therein does not affect the lubricated surfaces of any working parts of the engine which are not directly associated with the control of the incoming gas.

A still further object of the invention is to provide for a gas measuring arrangement which is applicable to one type of gas engine which is known to be very low in vibration and does not knock even when badly worn.

In the accompanying drawings:

Figure 1 is a vertical transverse section through one form of the improved internal combustion motor. Figure 2 is a vertical transverse section through a modified form of the motor.

Similar characters of reference indicate corresponding parts in both views.

The general scheme of this improved motor is to force combustible gas under pressure into a measuring chamber and then discharge the measured amount of gas into the engine cylinder. One feature of this arrangement is that said measuring chamber may be arranged close to the engine cylinder and thereby heated, so that the compressed gas which is caused to remain in said chamber for a short time is thoroughly vaporized by reason of the combined heat and pressure before being discharged into the cylinder and ignited. This broad application of the invention may be applied to any of the types of internal combustion motors now in use whether of the two-cycle or the four-cycle stroke.

For the purpose of illustration, however, the invention is shown as applied to a gasoline two-cycle engine 10 having a stationary, vertical cylinder 11, a crank case 12, a crank shaft 13, a piston 14, and a connecting rod 15 which is pivotally connected at its upper end to the wrist pin of said piston and is pivotally connected at its lower end to the crank pin 16 of the crank shaft. As is common practice in two-cycle engines, an exhaust port 17 is formed in one wall of the cylinder 11, which port is uncovered or opened by the descending piston 14 at the lower end of its stroke, so as to permit the spent exhaust gases in the cylinder to pass out of said exhaust port 17 into the atmosphere or into a suitable muffler in the usual and well-known manner.

After most of the spent gases have passed out of the cylinder through the exhaust port 17, the piston 14 continues to descend and uncovers a feeding vapor port 18 which is formed in the wall of the cylinder opposite to and somewhat lower than the exhaust port 17. Combustible gas or vapor is adapted to be forced under pressure from said feeding vapor port 18 into the cylinder and against a baffle plate 20 in the manner common to two-cycle engines, the pressure being derived from a suitable gas force pump 21. The gas passes into said force pump through an inlet gas pipe 22 wherein the pressure is comparatively low, the gas being derived from any suitable source such as the gasoline carburetor 25 shown in Fig. 2. Where a blower or velocity type of force pump is employed, a suitable check valve 26 may be arranged within the inlet gas pipe 22 to assist in maintaining a pressure for starting.

The rotary force pump may be power driven in any suitable manner, such as by the pump spur gear 27 which drives the said rotary force pump 21 and is in turn driven by an intermediate spur gear 28 that meshes with a driving gear wheel 30, which latter is secured to the crank shaft 13. Connected co-axially with said intermediate spur gear 28 is a rotary mechanically-operated or other suitable valve 31 which opens and closes in synchronism with the motor and controls the combustible gas which is ejected from the force pump 21 and delivered into a pre-heating and measuring chamber 32 through a port 33. The synchronous communication between said rotary valve and said force

pump may be denominated broadly as the action of a cut-off valve. Said chamber extends annularly completely around the engine cylinder so that the gas which is retained in said chamber for a short period of time is heated by reason of its contact with the cylinder wall and thus the gas is thoroughly vaporized by the combined simultaneous action of both the heat and 10 the pressure. This measuring chamber opens into the engine cylinder through the aforementioned feeding vapor port 18 which is located on the side of the engine which is opposite to the valve port 33 through which 15 the gas enters said measuring chamber. Thus the partially vaporized gas or vapor which enters the measuring chamber is caused to pass completely around the heated engine cylinder before being vented into the 20 interior of said cylinder through the feeding port 18 when the same is uncovered by the descending piston. This synchronous communication between the measuring chamber and the engine cylinder may be denominated as the action of an "inlet" valve. 25

The exact timing of the rotary valve 31 may be varied considerably according to the requirements of the engine and according to the type of the engine, and the valve itself 30 may be of any suitable type of mechanically-operated valve. The said valve 31 may be so timed as to open at any point in the cycle of operation subsequent to the rising of the top of the piston above the top edge 35 of the feeding port 18. The closing of said valve may occur at any time prior to the uncovering of said feeding port 18 by the descending piston. But in any case it is desired that the valve timing be such that the 40 said valve is closed whenever the feeding port 18 is opened. Otherwise, if a multiple cylinder engine (constructed in accordance with this invention) were to be started up, the gas would be forced from the force 45 pump right through the cylinder and out of the exhaust pipe, which action is not deemed desirable because of the danger and inefficiency involved and also because in such a case, the measuring action of the measuring 50 chamber would not be accurate.

In the modified engine construction shown in Fig. 2, a rotary valve 310 is employed whose hollow interior 320 acts in the capacity of a measuring chamber. In 55 this construction the speed of rotation of said valve 310 is half that of the crank shaft 13 and turns in the direction indicated by the arrows. Said valve is provided with two rotary valve ports 40 and 400, each of which 60 registers first with an outlet port 41 which communicates with the vapor force pump 21 and then registers with the feeding vapor port 18 which communicates with the engine cylinder. The registering successively of each of said rotary valve ports and

the communication effected with first the force pump and then the engine cylinder may be denominated as the action of a "cut-off valve" and of an "inlet valve", respectively. Thus the vapor is first forced from 70 the force pump through first one and then the other of said rotary valve ports and remains for an interval of time within the hollow interior 320 of the rotary valve 310, and then passes out through the same rotary 75 valve port into the engine cylinder, similarly to the action which occurs in the engine construction shown in Fig. 1. And similarly, also, there is no communication between the force pump 21 and the hollow 80 interior 320 of this modified rotary valve during the interval in which the feeding vapor port 18 is uncovered by the engine piston 14. And similarly also the compressed vapor, while remaining in said hollow interior 320 of the rotary valve, is subjected to the heating action of the cylinder. 85

The general operation of the engine is the forcing of an explosive hydrocarbon vapor from a force pump into a supplemental heating and measuring chamber and then cutting off communication between said chamber and said pump and allowing the compressed charge in said chamber to be discharged directly into the cylinder. Inasmuch as the vapor is highly compressed while the piston is at the bottom of its stroke, and inasmuch as the vapor is compressed still more when the piston rises, it is obvious that the entire ignition system of 90 the engine may be dispensed with where the pressures are sufficiently high. Such an arrangement however is not in most cases considered desirable where the fuel is mixed with the air before entering the engine cylinder. It is also obvious that the hydrocarbon liquid or gaseous fuel may be mixed 95 with the air at any point in the cycle of operations prior to the firing of the charge in the engine cylinder. For instance, for 100 certain classes of work, it is desirable to feed the fuel into the feeding vapor port 18, thereby avoiding all contact of the fuel with the rotary valve 31 or 310 of the force 105 pump 21.

The invention as a whole is unusually reliable in operation by reason of the positive feeding of a definitely measured and heated vapor charge to the engine irrespective of the engine speed. The mechanical construction is without weak trappy parts and is therefore not likely to get out of order. Very flexible engine control is obtained irrespective of atmospheric conditions and the engine involves no delicate machine work 110 in its construction and may be constructed at low cost.

I claim as my invention:

An internal combustion engine comprising a working cylinder, a piston reciprocating in 115

the cylinder and adapted during its backward stroke to compress a charge of fuel in the cylinder and to be moved forwardly with a firing stroke by an exploding charge 5 of fuel in the cylinder, means for supplying fuel, a measuring chamber having a fuel inlet adapted to connect with said fuel supply means and an outlet adapted to communicate with said cylinder, and valve 10 means which place the measuring chamber and cylinder in communication during the last part of the forward stroke of the piston and the first part of the backward stroke of the same and which cut off communication 15 between said fuel supply and the measuring chamber while the latter is in communication with said cylinder and place said fuel supply and measuring chamber in communication while communication between said measuring chamber and cylinder is cut off, whereby fuel is delivered from the fuel supply into the measuring chamber and the latter is filled so as to measure the quantity of fuel therein, then the measuring chamber is cut off from the fuel supply, and then this measured quantity of fuel is delivered to the cylinder during the last part 20 of the forward stroke and the first part of the backward stroke of the piston in the cylinder.

ROGER J. SWEET.
